UNITED STATES PATENT OFFICE.

BYRON DANLEY, OF ST. JOHNS, MICHIGAN.

POULTRY-COOP.

1,132,764.

Specification of Letters Patent. Patented Mar. 23, 1915.

Application filed September 14, 1912. Serial No. 720,323.

To all whom it may concern:

Be it known that I, BYRON DANLEY, a citizen of the United States of America, residing at St. Johns, in the county of Clinton and State of Michigan, have invented certain new and useful Improvements in Poultry-Coops, of which the following is a specification, reference being had therein to the accompanying drawings.

10 This invention relates to a portable shipping, exhibition, feeding or storage coop or crate for poultry and the object of the invention is to provide an arrangement thereof whereby sanitary conditions are maintained and the handling and feeding of the fowls facilitated.

15 A further object is to provide a cheap and compact construction having certain new and useful features in the construction and arrangement of parts, all as hereinafter more fully described and more particularly pointed out in the claims, reference being had to the accompanying drawings in which—

20 Figure 1 is a side elevation of a device embodying the invention with parts removed to show the construction; Fig. 2 is an end elevation of the same with portions broken away to show the construction and one of the doors in open position; Fig. 3 is an enlarged detail showing a central longitudinal section through a portion of the device and having parts broken away to shorten the figure; Fig. 4 is an enlarged 25 sectional detail showing a horizontal section through the device with portions broken away to shorten and narrow the figure; Fig. 5 is an enlarged transverse sectional detail; Fig. 6 is an enlarged detail showing an elevation of one of the doors; and Fig. 7 is a perspective view illustrating the door catch.

25 The poultry crate or battery consists of a suitable frame comprising corner posts 1 connected by longitudinal side sills 2, top strips 3, bottom end strips 4 and end top strips 5 making a rectangular frame of the desired size. This frame is supported upon caster rollers 6 which are secured to bars 7 extending across the frame and fastened to the sills 2. The frame is further provided with two longitudinal side bars 8 and transverse end bars 9, which end bars are arranged in pairs spaced apart to receive between them, trays 10 which are adapted to be slid endwise into the ends of

the structure between said bars and are supported by a series of cross strips 11. These trays are substantially one-half the length of the frame and are arranged to abut 60 transverse division strips 12 at their inner ends, which strips extend across the frame between side posts 13 positioned midway between the ends of the structure in each side of the frame. These trays thus divide 65 the structure into three stories or tiers of compartments and form tight dividing walls therefor.

70 The sides of the structure are closed by wire gratings 14 and a vertical row of doors 15 at each end of the crate. The end walls 75 of the crate are formed by strips 16 preferably of wire netting secured to the corner post 1 and between the transverse strips 9 to close the ends of each horizontal tier or 80 story of the structure. Each tier is divided into two compartments by transverse walls 17 of wire netting extending across between the posts 13 and secured at their upper and lower edges to the transverse 85 division strips 12. The whole structure is thus divided up into six separate compartments with a door 15 for each compartment through which access may be had to it to place the fowls therein and remove 90 them therefrom. A large number of fowls may thus be stored or shipped in a single 95 crate and separated into a number of groups so that they may have room to move about and sanitary conditions may be maintained. 90

100 The bottom or floor of each compartment is formed by a woven wire strip 18 which extends from one end of the structure to the other, each strip forming the floor for two compartments and extending over and supported by the cross strips 12 intermediate its ends. Each woven wire strip 18 is supported over and adjacent to the upper edge of one of the trays 10 and stretched tight so that it will not sag under the weight 105 of the fowls, by means of transverse bars 19 which are secured to the ends of the strips and these bars are each provided with horizontal openings at their ends to receive bolts 20 which pass therethrough and through holes in the corner posts 1. These bolts are screw-threaded at their outer ends and provided with nuts 21 which may be turned thereon against the outer faces 110 of the posts to draw the bars 19 toward the posts and stretch the woven wire strip longitudinally. These bottoms being

stretched to a high tension, act as the members for the frame between its corner posts and make a very rigid structure. If the strips become slack under the weight of the fowls they may be tightened at any time by turning up the nuts on the bolts and thus the fowls are supported by a smooth floor of woven wire and their feet kept in a clean, sanitary condition thereby. The 10 side bars 8 and cross strips 9 and 12 are all beveled at their upper edges so that no dirt will lodge thereon and the sides and ends of the trays are also beveled for the same purpose. These trays are arranged 15 to catch all the dirt and litter and may be quickly and easily removed for the purpose of cleaning, thus making the crate very sanitary.

Suitable troughs 22 are provided with 20 hooks 23 (see Fig. 5) so that they may be hung upon the grating 14 at the sides of each compartment and this grating is preferably formed of straight vertical and horizontal wires which are welded or otherwise 25 united at their points of intersection, thus forming a grating, the openings in which are rectangular and elongated vertically so that the fowls may readily extend their necks through these openings and eat out of 30 the troughs.

The doors 15 are preferably formed by a wire grating similar to the sides 14 and they are hinge connected to the posts 1 by means of staples 24 embracing the vertical wire 25 35 at the back edge of the door and driven into the posts, one staple being preferably placed above and another below each of two of the horizontal wires 26 of the door. The staples by embracing the wire 25, form a pivotal 40 connection for the door and by their engagement with the upper and lower sides of the horizontal wires 26, they prevent the door from moving vertically and hold it firmly to swing in a horizontal plane. A 45 hook or latch is provided for each door by extending one of the horizontal wires 26 beyond the forward edge of the door and bending it into a laterally extending hook 27 which is adapted to engage over the corresponding horizontal wire 28 of the side 50 grating 14. The downwardly bent end 29 of the hook is extended somewhat so that the hook cannot be disengaged from the wire 28 without lifting the forward edge of the door; and as the door is held against such lifting movement by the staples 24, it will be necessary to spring the grating and thus the hook is firmly held in engagement with the wire 28 and the door in locked position, 55 by the resiliency of the door itself. All liability of the doors becoming unhooked during shipment or handling of the crate is thus obviated.

In this construction a portable crate or 60 what is known to the trade as a "poultry

battery" is provided which will keep the fowls clean and in a healthy condition and the construction is such that it is cheap to manufacture and is very light and strong.

Obviously changes may be made in the 70 construction and arrangement of parts without departing from the spirit of my invention and I do not limit myself to the form or arrangement shown.

Having thus fully described my invention what I claim is:—

1. In a poultry battery, the combination of a rectangular frame comprising side sills, corner and intermediate posts, spaced end strips connecting the corner posts, and 80 transverse strips between the intermediate posts, wire grating forming the sides of the structure, end walls, transverse walls of wire between the intermediate posts, woven wire strips dividing the interior of the 85 frame into horizontal tiers of compartments and extending from end to end of the structure, strips secured to the ends of the woven wire strips, adjustable means carried by said corner posts and engaging the 90 said strips on the wire strips to stretch the wire strips longitudinally, and trays 95 slideable between the spaced end strips beneath the woven wire bottoms and abutting the transverse strips between the intermediate posts.

2. In a poultry crate, a structure divided into horizontal tiers of compartments, a pair of trays movably mounted in the outer ends of pairs of the compartments of said structure and having their inner ends terminating at a point centrally of said structure whereby said trays form the bottom of each pair of compartments, and adjustable woven wire strips extending from one end of said 105 structure to the opposite end thereof above each pair of trays.

3. In a poultry crate, a structure having posts connected by foraminous walls, strips of inter-woven wires horizontally disposed 110 within said structure and adjustably supported by said posts, transverse division strips supporting said inter-woven wire intermediate the ends thereof; foraminous partitions supported between said strips of 115 inter-woven wire and having the upper and lower edges connected to said division strips; and dividing said structure into a plurality of superimposed compartments, and trays movably supported beneath said 120 strips of inter-woven wire.

4. In a poultry crate, the combination with a structure comprising posts and sides, ends and a top, of a bottom formed by a strip of woven wire, foraminous partitions 125 having the lower edges thereof held in engagement with the strip of woven wire; bars secured to the ends of said strip, bolts engaging openings in said bars and openings in said posts, and nuts in the outer ends of 130

said bolts to draw the same through the openings in said posts and stretch the woven wire strip.

5. In a poultry crate, a structure having
posts connected by foraminous walls, strips
of inter-woven wire horizontally disposed
within said structure and supported by said
posts, foraminous partitions having the
lower edges thereof extending through said
10 inter-woven wire; means extending through

said posts to adjust and facilitate stretching
the said strips of wire, and trays movably
supported beneath said strips of wire.

In testimony whereof I affix my signature
in presence of two witnesses.

BYRON DANLEY.
